SLIDE FASTENER

Louis W. Schaaff, Jackson Heights, N. Y., assignor
to Waldes Koh-I-Noor, Inc., Long Island City,
N. Y., a corporation of New York

Application August 7, 1941, Serial No. 405,857

12 Claims.

(Cl. 24—205)

This invention relates to improvements in slide fasteners, and in its more specific aspects, to improvements in sliders therefor and in the construction and mode of securement of the pull tabs for operating the same.

Considered generally, sliders as heretofore constructed employ for their operation pull tabs of rigid metallic construction which are secured to the slider by a rivet or like securing means whose head protrudes a substantial distance from the front face of the slider body, or which is otherwise provided with a hook-like extension also projecting out of the plane of the slider front face. Obviously, such securing means add to the overall depth and bulk of the slider body, and moreover, pull tabs of the stated character in many cases are bent or deformed in use to a degree impairing if not destroying their usefulness. Where the prior sliders employed pull tabs of a flexible nature such as chains or fabric tapes, their securement to the slider body generally followed the same mode of securement characterizing pull tabs of the rigid metallic type, with the disadvantages attendant to the latter.

The present invention contemplates and aims to provide a novel and improved slider and pull tab assembly employing a flexible type pull tab which overcomes the above-noted disadvantages of the prior devices, while at the same time providing a slider assembly of minimum overall depth which can be readily manufactured and assembled in quantity, which is commercially practical and effective in operation, which requires as its fastening means no hook-like or other rivet head formation extending from the plane of the front face of the slider body, and which in addition incorporates an effective mode of securing the pull tab to the slider body.

The invention also has for a major object the provision of a novel slider construction which lends itself admirably to the use of pull tabs of flexible nature, and also to pull tabs which may be operated from either side of the slider when the fastener is applied to reversible garments and which further of itself represents an advance and improvement in slider body construction and design.

Moreover, the slider and pull tab construction of the present invention is one of pleasing design and appearance, and is of the character permitting a high order of embellishment not possible with sliders of known construction.

Other objects will be in part obvious and in part hereinafter pointed out in connection with

the following analysis of this invention wherein is illustrated an embodiment of the invention in detail.

In the drawing—

5 Fig. 1 is a plan view of a portion of a slide fastener employing a slider which incorporates the improvements of the present invention.

Fig. 2 is a part section view taken vertically through the slider illustrated in Fig. 1.

Fig. 3 is a horizontal section taken along line 3—3 of Fig. 1.

Fig. 4 is a part sectional view through a slider employing a modified form of pull tab.

15 Fig. 5 is a section view, similar to Fig. 3, illustrating a modified form of slider construction.

Figs. 6 and 7 are respectively front and side views of a modified form of slider and pull tab assembly in accordance with the present invention.

20 Referring to the drawing wherein like reference characters designate like parts throughout the several views, reference characters 10, 11 designate conventional fastener elements arranged in row formation along the edges of opposed stringers 12, 13, the latter being in turn secured along the edges of an opening in a garment or like article which is adapted to be closed upon interlocking of meshing of the elements, and to be opened upon disengagement of the elements. As is well known the fastener elements are adapted to be interlocked and disengaged by a slider S which embraces the elements and which operates, when moved in one direction, generally upwardly, to progressively force the elements into interlocking engagement, and when moved in the opposite direction, generally downwardly, to progressively disengage the elements.

25 The slider S which incorporates the improvements of the present invention is shown to have the general form and mode of operation of the slider disclosed in my copending application Serial No. 395,479, filed May 27, 1941, insofar as the self-locking features of the latter and its ability to dispose the rows of disengaged fastener elements parallel upon their exit from the head opening provided therefor, is concerned. However, it is to be clearly understood that the present invention is not limited to sliders of the form disclosed in my prior application aforesaid but on the other hand is applicable as well to sliders of the so-called standard design which are provided with a Y-shaped race for the fastener elements and which in operation dispose the disengaged fastener elements fanwise.

As illustrated, the slider body S is constituted by front and rear plates 15, 16 each having marginal side flanges 17, 18, and an elliptically shaped divider or separator for the fastener elements generally designated 20, the latter being disposed well within the slider body and at or near the geometric center thereof. The slider body is provided with a top or head opening for the entry and exit of disengaged elements and with a bottom or tail opening for the entry and exit of the engaged fastener elements. In the illustrated slider, the front and rear plates and side flanges, and the more or less centrally disposed divider 20, cooperate to provide an open-ended race for the fastener elements having upper and lower straightway race portions disposed in longitudinal alignment, and connecting branch portions which diverge outwardly from one straightway portion and thence inwardly into the other straightway portion.

Improvements incorporated into the slider as aforesaid, according to the present invention, relate to the construction of the divider 20 and to the manner of securing a pull tab in the nature of a flexible cord, thong tape or the like thereto. Referring particularly to Figs. 2 and 3, wherein the improved divider construction is illustrated, one of the slider plates, such as the rear or under plate 16, has integrally formed thereon as by a die-forming operation an elliptical divider section 20a having a base portion 21 terminating in an inwardly directed abutment shoulder 22, and a sleeve-like extension 23 which projects relatively upwardly from the base portion 21. The height of the base portion is one-half that of the complete divider, the height of the sleeve portion being somewhat greater than the height of the base portion for the purpose to be described.

The divider section 20a as constituted by the base and sleeve portions 21, 23 thereof is formed with a through bore or aperture which may be of circular or of substantially circular section, the aperture widening out at its end adjacent the rear plate 16 along a gentle curvature, thus to provide a curved seat or bearing to be hereinafter referred to.

The related front plate 15 carries an integral divider section 20b of height half that required for the complete divider, such being preferably die-formed therein to extend from the underface of the plate. Divider section 20b is provided with a bore or opening, the inner end of which is of a size and interior formation as to snugly receive the sleeve portion 23 of the companion divider section 20a, the outer end of said opening being enlarged along a gradual curvature.

In assembly, the divider section 20b is threaded or telescoped on to the sleeve extension 23 of divider section 20a, and the plates 15, 16 are forced relatively towards each other until the end face of divider section 20b abuts against and seats on shoulder 22. With the parts assembled as aforesaid, the slider plates are spaced a predetermined distance as required. Due to the sleeve extension 23 being formed long, its end projects slightly beyond the face of the outer plate 15. Thereupon this projecting end is deformed or upset to a degree causing it to bear tightly on the curved, enlarged end of the through opening of divider section 20b. The extra length of the sleeve extension 23 is taken up in the upsetting or riveting-over operation, so that following final assembly, the sleeve is wholly confined within the front and rear planes of the

slider body and plates 15, 16 are securely held in properly spaced relation as is required.

Upon the assembly aforesaid, the divider sections cooperate to provide a tubular divider in which the bores or openings of the divider sections form an opening through the slider. Moreover, by reason of the disposition of the divider sections at the approximate geometric center of the slider plates, the assembled slider body is substantially crush-proof to pressures that tend to crush or impair the utility of sliders of conventional construction.

Preferably, the outer face of each slider plate is countersunk simultaneously with the formation of its divider section, to provide a circular recess 26 disposed about but on the other side of the plate from the divider section carried thereby. This recessing of the plates, in conjunction with the enlargement of the divider section bores adjacent the relatively outer ends thereof, provide substantial space inwardly of the outer plane of the slider plates for the accommodation of the pull tab end or the securing means therefor.

With the construction so far described, it will be seen that the slider is "rivetless" in the sense that no separate rivet is employed to secure the front and rear plates of the slider in their required spaced parallel relation. Moreover, the divider itself provides the sole means for securing the plates in properly spaced relation and, by reason of its construction and non-circular cross-sectional shape, also functions to prevent relative turning of the plates. This rivetless construction makes for extreme thinness of slider body and due to the absence of any protruding head or equivalent means for securing the slider plates together results in a slider causing no appreciable bulging when worn on either outer or inner garments.

The slider body construction as described lends itself admirably to the securing of pull means thereto, particularly when such means are of the pull cord type, which by reason of their flexibility permit the slider to slide without the customary twisting friction characterizing standard pull tabs of rigid construction. Referring to Fig. 2, the pull cord 28 there shown is of the flexible type, being woven from textile strands or being in the form of a leather thong, or being fashioned from plastic material. One end of the flexible pull cord is threaded through the open-ended bore of divider section 20a, and its terminal end may be knotted but is preferably enclosed within a bead 30 of diameter larger than the through bore. By reason of the countersinking of the rear plate and the enlargement of the end of the cord receiving bore adjacent thereto, the bead 30 normally seats against the curved seat formed at the relatively inner end of the bore and hence the bead does not protrude out of the plane of the rear face of the slider, but on the other hand is accommodated within the space provided by the countersinking and enlargement of the bore end. The other end of the pull cord 28 may be provided with a bead 32 of relatively greater diameter, which is readily grippable for moving the slider in either direction along the rows of fastener elements.

Referring to Fig. 4 wherein a modified form of pull cord is illustrated, the pull cord 34 is of sufficient length as to extend equally from both faces of the slider, its intermediate portion being disposed within the bore of divider section 20a. The pull tab is provided adjacent each face of the slider with metallic rings or bands 35, 36 of

diameter insuring that the tab cannot be separated from the slider when pull is exerted on either end.

The pull tab arrangement illustrated in Fig. 4 is of the character making it admirably suited for use with the sliders for slide fasteners applied to reversible garments. Thus, by the provision of a unitary pull tab having ends projecting from both faces of the slider, the latter may be actuated from either face of the garment, depending upon which side is disposed outwardly.

In Fig. 5 there is illustrated another form of slider employing a modified construction of divider functioning as a spacer for the slider plates. Such a slider is constituted by spaced plates 40, 41 of identical construction, the outer faces thereof being each provided with a countersunk recess 42 of circular formation, each recess being pierced to provide an elliptical aperture. A separately formed elliptical divider (and spacer) element 43 is adapted to extend between the plates, the ends being undercut as at 44 to provide shoulders which are spaced slightly from the end edges thereof. With the divider element being extended a slight distance beyond the ends of the shoulders 44, the extending end portions are adapted for deformation during assembly. In the assembly operation, the slider plates 40, 41 are threaded over the deformable ends of the divider 43 until they bear against the end shoulders 44, and thereupon the extending ends are upset or riveted over in the manner shown to secure the plates 40, 41 in their spaced parallel relation as is required. It is noted that the ends of the divider upon their upsetting seat in the countersunk recesses 42 and thus do not protrude beyond the plane of the outer faces of the slider.

The divider element 43 is provided with a through bore 45 through which a cord, such as the cord 28 of the Fig. 2 construction, or the cord 34 of the Fig. 4 construction, is adapted to be threaded and secured. By suitably enlarging the ends of the bore 45 along a gentle curvature, the beaded end of the pull cord is appropriately accommodated so that its securing bead or equivalent is disposed within the planes of slider.

Referring to the further modification illustrated in Figs. 6 and 7, the divider there illustrated may be of the sectional character illustrated in my copending application aforesaid and employs a securing rivet 50 extending through the divider half sections which operates to secure the slider plates 51, 52 in spaced parallel relation. The head 53 of the rivet 50 is adapted to seat in a circular recess 54 countersunk into the front face of one slider plate 52, the countersinking in the modified form of the invention under description being appreciable so as to provide a relatively deep recess for the rivet head.

By reference particularly to Fig. 6, the rivet head 53 is in the nature of an elongated ridge, the outer surface of which extends along a curvature, whereby only the mid portion of the head extends out of the plane of the upper or front face of the slider. The head is provided with a transverse opening for the reception of a pull tab 55 of ribbon or tape-like form, preferably of textile material, which is threaded through the rivet opening and fastened to the rivet head by a ring or clip 56. The color of the ribbon-like pull tab may be matched with the color of the garment to which the fastener is applied, and hence a slider and pull tab assembly having an attractive and pleasing appearance is provided.

Without further analysis, it will be seen that the invention provides a slider for slide fasteners incorporating effective and practical means for securing the slider plates in their spaced parallel relation, and that this construction lends itself admirably to the securing of pull tabs of the flexible type to the slider body. Moreover, sliders constructed in accordance with the invention have minimum thinness and overall bulk by reason of the fact that the slider is devoid of any rivet or rivet head which protrudes substantially from the upper or under faces of the slider body. Hence, not only a slider of extreme thinness is provided, but also no appreciable bulging of garments disposed over the garment fastened by sliders of the present invention can result.

Moreover, the present invention provides a double-sided unitary pull tab for a reversible slider which can be used with reversible garments and thus represents a distinct advance in the art of sliders adapted for reversible use.

As will be apparent from Figs. 1 and 6, for example, the slider of the present invention is of pleasing design and appearance, and provides in addition substantial face area for embellishment when and if such is desired.

As many changes could be made in carrying out the above constructions without departing from the scope of the invention, it is intended that all matter contained in the above description, or shown in the accompanying drawing shall be interpreted as illustrative and not in a limiting sense.

I claim:

1. A two-part slider for slide fasteners comprising front and rear plates having marginal side flanges, one of said plates being provided with an integral divider section comprising a body portion terminating in an abutment shoulder and an extension projecting relatively upwardly therefrom, the other plate being provided with an integral divider section disposed about said extension in continuation of said body portion and forming with the latter a full depth divider, the end of the last-named divider section abutting said shoulder and the end of the extension providing means operatively securing the divider sections one to the other and the plates in spaced parallel relation, whereby said plates with their side flanges and the divider provide a race for the engaged and disengaged elements.

2. A two-part slider for slide fasteners comprising front and rear plates having marginal side flanges, one of said plates being provided with an integral divider section comprising a body portion terminating in an abutment shoulder and a sleeve-like extension projecting relatively above said shoulder, said body portion and extension being provided with a through opening, the other plate being provided with an integral divider section disposed about said extension in continuation of said body portion and forming with the latter a full depth divider, the end of the last-named divider section abutting said shoulder and the end of the extension providing means operatively securing the divider sections one to the other and the plates in spaced parallel relation, whereby the secured plates with their side flanges and the divider form a race for the engaged and disengaged fastener elements.

3. A slider for slide fasteners comprising front and rear plates having marginal side flanges, the plates being each provided with an aperture, a divider adapted to extend between plates with its

ends extending into the plate apertures and being provided near each end thereof with a shoulder against which an adjacent plate bears, the ends of the divider beyond said shoulders providing means operatively securing the plates against the shoulders and the plates in spaced parallel relation, whereby the plates, the side flanges thereof and the divider cooperate to form a race for the engaged and disengaged fastener elements.

4. A slider for slide fasteners comprising front and rear plates having marginal side flanges, the plates being each provided with an aperture, a divider adapted to extend between plates with its ends extending into the plate apertures and being provided near each end thereof with a shoulder against which an adjacent plate bears, the ends of the divider beyond said shoulders providing means operatively securing the plates against the shoulders and the plates in spaced parallel relation, whereby the plates, the side flanges thereof and the divider cooperate to form a race for the engaged and disengaged fastener elements, said divider being hollow to provide an opening through the slider for the reception of a pull tab or the securing means therefor.

5. In a slider and pull tab assembly, a slider comprising separate front and rear plates, a divider providing the sole means for securing the plates in spaced parallel relation and against relative turning movement and providing an opening through the slider which opening is enlarged at one end thereof to form a seat, a pull tab extending through the opening and having at one end thereof a bead adapted to engage said seat and thereby to be disposed relatively inwardly of the outer face of the adjacent plate.

6. A slider for slide fasteners comprising separate front and rear plates having marginal side flanges, a tube-like divider of non-circular cross-section disposed approximately at the geometric center of said plates, said divider providing the sole means for connecting, properly spacing and prevent relative turning of said plates and forming with said plates and the side flanges a race for the fastener elements, the opening through said divider being shaped to provide a pull tab bearing, and a flexible pull tab extending through said opening and having retaining means disposed substantially within the confines of the relatively outer faces of the plates.

7. A slider for slide fasteners comprising separate front and rear plates having marginal side flanges, a tube-like divider of non-circular cross-section disposed approximately at the geometric center of said plates, said divider providing the sole means for connecting, properly spacing and prevent relative turning of said plates and forming with said plates and the side flanges a race for the fastener elements, said divider including a divider section integrally connected with one of said plates, the opening through said divider being shaped to provide a pull tab bearing, and a flexible pull tab extending through said opening and having retaining means disposed substantially within the confines of the relatively outer faces of the plates.

8. A slider for slide fasteners comprising separate front and rear plates having marginal side flanges, a tube-like divider of non-circular cross-section disposed approximately at the geometric center of said plates, said divider providing the sole means for connecting, properly spacing and prevent relative turning of said plates and form-

ing with said plates and the side flanges a race for the fastener elements, said divider being formed by divider sections each integral with a plate, the opening through said divider being shaped to provide a pull tab bearing, and a flexible pull tab extending through said opening and having retaining means disposed substantially within the confines of the relatively outer faces of the plates.

10. 9. A slider for slide fasteners comprising separate front and rear plates having marginal side flanges, a tube-like divider of elliptical cross-section disposed approximately at the geometric center of said plates, for connecting, said divider providing the sole means properly spacing and preventing relative turning of said plates and forming with said plates and the side flanges a race for the fastener elements, the opening through said divider being shaped to provide a pull tab bearing, and a flexible pull tab extending through said opening and having retaining means disposed substantially within the confines of the relatively outer faces of the plates.

15. 10. A slider for slide fasteners comprising separate front and rear plates having marginal side flanges, a tube-like divider of elliptical cross-section disposed approximately at the geometric center of said plates, said divider providing the sole means for connecting, properly spacing and prevent relative turning of said plates and forming with said plates and the side flanges a race for the fastener elements, said divider having one end integral with one of said plates and its other end countersunk in the other of said plates, the opening through said divider being shaped to provide a pull tab bearing, and a flexible pull tab extending through said opening and having retaining means disposed substantially within the confines of the relatively outer faces of the plates.

20. 11. A slider for slide fasteners comprising separate front and rear plates having marginal side flanges, a tube-like divider of elliptical cross-section disposed approximately at the geometric center of said plates, said divider providing the sole means for connecting, properly spacing and prevent relative turning of said plates and forming with said plates and the side flanges a race for the fastener elements, said divider having its opposite ends countersunk into said plates, the opening through said divider being shaped to provide a pull tab bearing, and a flexible pull tab extending through said opening and having retaining means disposed substantially within the confines of the relatively outer faces of the plates.

25. 12. A slider for slide fasteners comprising separate front and rear plates having marginal side flanges, a tube-like divider of elliptical cross-section disposed approximately at the geometric center of said plates, said divider providing the sole means for connecting, properly spacing and prevent relative turning of said plates and forming with said plates and the side flanges a race for the fastener elements, the opening through said divider being shaped to provide a pull tab bearing, and a flexible pull tab extending through said opening and having retaining means disposed substantially within the confines of the relatively outer faces of the plates, said pull tab being disposed so that its ends extend to both sides of the slider and said retaining means fixing it against endwise sliding movement through the divider opening.

LOUIS W. SCHAAFF.
